UNITED STATES PATENT OFFICE.

CHARLES B. KENT, OF KENOSHA, WISCONSIN.

DESIGN FOR A CARBURETER.

47,304.

Specification for Design.

Patented May 4, 1915.

Application filed August 15, 1914. Serial No. 856,995. Term of patent 7 years.

To all whom it may concern:

Be it known that I, CHARLES B. KENT, a citizen of the United States, and a resident of Kenosha, in the county of Kenosha and State of Wisconsin, have invented a new, original, and ornamental Design for Carbureters, illustrated on the accompanying drawing, in which—

Figure 1 is a side elevational view, and Fig. 2 is a plan view.

I claim:

The ornamental design for a carbureter, as shown.

CHARLES B. KENT.

Witnesses:

FLORENCE McGREAL,
FLEMING G. RENNIE.
